COMBINATION GAS HEATER

Edwin C. Adams, Pittsburgh, Pa.

Application March 6, 1931. Serial No. 520,572

5 Claims. (Cl. 126—90)

My invention relates to room heaters and particularly to combination radiant and circulator gas heaters.

An object of my invention is to provide a relatively simple, compact, and highly efficient combination radiant and circulator heater structure.

Another object of my invention is to provide a combined radiant and circulator gas heater in which the venting between the heater and the circulator or heat exchanger is confined to the area of the combustion space within the radiants.

Another object of my invention is to provide means in a combination radiant and circulator heater that shall ensure the complete combustion of the gas within the combustion space in the radiants, under abnormal operating conditions as well as under normal operating conditions.

Another object of my invention is to provide means for effecting a highly efficient heat-interchange, said means permitting of an auxiliary flow of air to be heated, in addition to the main flow of air.

A still further object of my invention is to provide means permitting the adjustment by relatively simple means of the amount of or the speed of travel of the products of combustion through the heat-exchanger.

Other objects of my invention will either be apparent from the description of the device embodying my invention or will be pointed out in the course of said description.

In practicing my invention, I provide a suitable housing, the greater portion of which may be made of sheet metal elements, the housing having an open front in which is located a back wall of a refractory material, in which are located a plurality of open face radiants providing the combustion space for the gas burned therein by a suitable gas burner located below the radiants. This plurality of radiants is used for convenience of manufacture and replacement and a single large radiant unit may be used. A heat-exchanger providing one path for the products of combustion and another path for the air to be heated, is located within the housing, and has inlet and outlet openings respectively for the products of combustion. A grill in the front upper portion of the housing provides an auxiliary path for air to be heated. An adjustable baffle is located within the heat-exchanger.

In the single sheet of drawing,

Figure 1 is a view, in front elevation, of a combined radiant and circulator heater embodying my invention, only one radiant being shown therein.

Fig. 2 is a view, in side elevation, of the device shown in Fig. 1.

Fig. 3 is a view, in vertical lateral section, of the device embodying my invention and taken on the line III—III of Fig. 1.

Fig. 4 is a view, in horizontal section, taken on the line IV—IV of Fig. 3, and,

Fig. 5 is a view, in rear elevation, of a radiant used in my improved heater.

While I have illustrated in the drawing and will now describe a particular embodiment of a structure either embodying my invention or with which the devices particularly embodying my invention are operatively associated, I desire it to be understood that this is done for illustrative purposes only, and that I do not desire to be limited to the particular details of construction shown as these illustrate that form of the device embodying my invention best adapted to practice the same.

A heater housing designated by 11 may include an ornamental open front member 12 and an open top box structure 13 associated therewith. Legs 14 and 16 of any suitable type and design may be provided and secured in any well known manner to the box 11. A perforated cover 17 is located on the top of the casing and may be held thereagainst by any suitable means (not shown). The member 12 may be made of a suitable ornamental light-weight casting in order that the heater may have a pleasing front appearance. The member 12 may include a lower projecting ledge 18 and an upper portion 19 also projecting forwardly of the plane of the side portions thereof and the lower arcuate part of portion 19 may be perforated as shown at 21 in Figs. 1 and 3 of the drawing for a purpose to be hereinafter set forth.

A clay back wall 22 of substantially inverted L-shape, and while I have shown a refractory back wall of relatively large mass, I do not desire to be limited thereto, as the back wall might be made of metal and of relatively small mass, or the front wall of the heat-exchanger unit to be later described may serve the same purpose. The construction and materials I have selected are those suited for long life. The back wall is provided with an outlet opening 23 therethrough, which opening is substantially as wide as the space occupied by a plurality of open face radiants 24, which radiants may be of any suitable or desired type usually employed in radiant gas heaters. The size and shape of the individual radiants 24 is such that their upper end portions fit relatively closely within the overhanging and

downwardly-extending portion 26 of the back wall. By closely fitting I do not desire to convey the impression that there can be no clearance between the two members 26 and 24, but I do 5 wish to point out that the fit therebetween shall be close enough so that practically little or no air will enter the outlet 23 in the clearance space therebetween, thus making it necessary that all of the air required for the proper combustion of 10 gas being burned within the radiants, shall enter the radiants either at the bottom or through the open face fronts thereof.

A gas burner manifold 27 is suitably supported within the housing 11 in proper operative position 15 below the radiants 24 and a gas valve 28 is provided in a manner well known in the art to control the amount of gas being burned. I have not shown a supporting means for the manifold as any suitable or desired means of this kind may 20 be employed. It is further to be understood that the back wall is suitably supported on a plane support 29 which may be a separate plate provided for that purpose, or which may be a part of a heat-exchanger now to be described.

25 A heat-exchanger 31 includes a boxlike structure which is substantially closed at four sides thereof, and which is provided with a plurality of conduits 32 therein extending in a vertical direction and located in spaced relation relatively 30 to each other. The walls of the conduits at their ends are suitably secured to the top and bottom walls of the heat-exchanger structure to prevent products of combustion flowing out of the heat-exchanger at any point other than a flue 33 at 35 the rear thereof, which flue fits into an outlet opening 34 in the rear wall of housing 11 and which is provided for connecting the heater to a chimney or stack flue in the usual fashion. The heat-exchanger 31 is provided with a relatively 40 narrow but relatively long inlet opening 36 which fits into the outlet opening 23 in the back wall 22.

45 A baffle structure 37 includes a vertically-extending plate 38 and a horizontally-extending plate 39 pivotally mounted at one of its edges to the lower end of the vertical portion and having its free end formed to project forwardly between and around the conduits 32, the baffle being located between the conduits 32 and the 50 back wall of the heat-exchanger 31. An adjusting knob 40 may be located at the side of the casing 11 to permit of adjusting the position of portion 39 for regulating the flue draft.

55 While proper and complete combustion of the gas will take place within the radiants themselves and before the products of combustion reach the outlet opening 23, so long as normal oxygen-supply conditions prevail, it may happen that a gas heater of this kind will be called upon 60 to operate in a substantially closed chamber or room, and I have found that complete combustion will not occur entirely within the radiants under these conditions. In order to supply an auxiliary amount of oxygen which will ensure the 65 complete combustion within the radiants themselves, I provide two relatively small openings 41 in the back wall of each radiant. Cooperating 70 with these openings are a pair of grooves 42 (see Fig. 1) located in the front surface of the back wall and extending from the bottom edge thereof and up to substantially the top edge of openings 41, thus conducting combustion air to the radiants at a most advantageous point for insuring complete combustion.

75 A radiant-type gas-fired room heater has cer-

tain advantages among which may be mentioned that a heater of this type will develop heat very quickly from a cold start, will keep warm the floor of a room in which it is located, and will also provide the cheerful and penetrating radiant heat that comes from a glowing fire. However, 80 in order to obtain all of these advantages it is essential that the front of the heater be open as any known practical transparent enclosure will prevent the passage therethrough of a relatively large percentage of the radiant heat. The radiant efficiency of a radiant type of heater ranges from about 25% to about 30%, and if a radiant heater is used in a fully vented fireplace, the above mentioned efficiency will be about the maximum that can be obtained. In order to increase the efficiency circulator heaters were 85 designed but these had to be constructed along different lines in order to be efficient, and when both types were combined in a single structure concessions had to be made in order to get the desired higher efficiency.

90 In the device embodying my invention the construction and arrangement of the radiants and the back wall is such that the combustion is effected completely in the combustion space with 95 in the clay radiants, and due to the close fit of the upper ends of the radiants in the openings in the back wall the amount of air entering the heat-exchanger is limited substantially to that 100 necessary to provide or effect the complete combustion of the fuel consumed within the radiants or, in other words, the air and gas entering the radiants. The fit of the radiants within the back wall is, as has already been hereinbefore set forth, 105 such that relatively little air may enter the outlet opening 23 by flowing past the upper ends of the respective radiants or between the upper ends of the radiants and the back wall itself. The exclusion of any excess air from the flue spaces 110 beyond the combustion space within the radiants themselves, ensures that the gases of combustion will have the highest possible temperature 115 when they enter the heat-exchanger, thus causing a higher differential of temperature between 120 the air to be heated and the metal walls of the heat-exchanger. It may here be stated that if it were possible to supply exactly the required amount of air to completely burn natural gas, an 125 analysis of the flue gases would show about 12% of CO₂, but I have found as the result of many tests, that so much excess air enters a radiant heater of the usual kind that the percentage of CO₂ is about 1½%. In well designed totally 130 enclosed heaters the secondary air openings are made of such size as to supply only enough secondary air to support complete combustion, but because this secondary air cannot be directed perfectly into the flame the percentage of CO₂ rarely exceeds 5% to 6%. Tests on a number of gas 135 heaters embodying my present invention have shown that the percentage of CO₂ is 9½%, or over 75% perfect, and I attribute this to the fact that the amount of excess air mixed with or becoming a part of the gases of combustion is relatively 140 very small.

145 It is obvious that convection currents of heated air will flow upwardly in the conduits 32, which are open at both ends, in the direction indicated by the arrows 46, this main path being substantially free and unobstructed. The products of combustion will flow in a circuitous path, indicated by the arrows 47, in the heat-exchanger and out through the flue 33. Because of the 150 circuitous path traversed by the products of com-

bustion a very large percentage of the heat in the products of combustion will be transferred into the air flowing through the conduits 32.

The upper part of the back wall, and particularly the overhanging portion 26 will be raised to a relatively high temperature so that an auxiliary path for convection currents of air will be established through the openings 21 in the grill and upwardly out through the perforated cover 17, this air being heated not only by the upper portion of the back wall but also by the upper portion of the heat-exchanger.

Another advantage of my invention as illustrated is that an operator or user of a gas room heater of my improved type may obtain any desired degree of humidity within a relatively wide range, by merely varying the position of the baffle plate, as has been hereinbefore set forth because this baffle controls the amount of the products of combustion which may be projected back into the room and, as such products contain moisture, humidity control results.

The device embodying my invention thus provides a highly efficient combined radiant and circulator heater, the dimensions whereof are a minimum because of the relatively high temperatures at which the products of combustion enter the heat exchanger. It provides also means for obtaining relatively strong main and auxiliary convection currents of heated air, and a person or object within range of the radiant heat from the front of the heater will be subject to the radiant heat therefrom. The degree of humidity in the room can also be controlled by the adjustment of the baffle in the heat exchanger.

I desire that my invention be limited only by the prior art, and in accordance with the appended claims.

I claim as my invention:—

1. A heating appliance comprising in combination an open-front radiant heater consisting of an outer housing having an opening in its front, a perforated cover on its top, and an outwardly projecting portion above said front opening perforated on its under side to permit the circulation of air through it and out said cover, a burner supported in said housing back of said front opening, a heat-reflecting back wall mounted in the rear of said burner, a radiant mounted over said burner with its upper end engaged in an orifice in said back wall and in such a way that only the products of combustion passing through said radiant are permitted to pass through said orifice, an enclosed circulator chamber forming casing mounted back of said back wall in spaced relation to said outer housing, an inlet connection connecting said casing to the orifice in said back wall, a flue connection extended from said casing through said housing, and an open ended circulating conduit extended vertically through said circulator chamber.

2. A heating appliance comprising in combination an open-front radiant heater consisting of an outer housing having an opening in its front, a perforated cover on its top, and an outwardly projecting portion above said front opening perforated on its under side to permit the circulation of air through it and out said cover, a burner supported in said housing back of said front opening, an inverted substantially L-shaped heat-reflecting back wall mounted in the rear of said burner, a radiant mounted over said burner with its upper end engaged in an orifice in said back wall and in such a way that only the products of combustion

passing through said radiant are permitted to pass through said orifice, an enclosed circulator chamber forming casing mounted back of said back wall, an inlet connection connecting said casing to the orifice in said back wall, a flue connection extended from said casing through said housing, an open ended conduit extended vertically through said circulator chamber, and a baffle wall structure in said casing arranged to provide a circuitous path for the products of combustion through said circulator chamber.

3. A heating appliance comprising in combination an open-front radiant heater consisting of a burner, a heat-reflecting back wall mounted in the rear of said burner, a radiant mounted over said burner with its upper end engaged in an orifice in said back wall and in such a way that only the products of combustion passing through said radiant are permitted to pass through said orifice, an enclosed circulator chamber forming casing mounted back of said back wall, an inlet connection connecting said casing to the orifice in said back wall, a flue connection in the side of said casing opposite said back wall, a baffle wall structure in said casing arranged to provide a circuitous path for the products of combustion through said circulator chamber, and an adjustable baffle wall portion mounted on one end of said baffle wall and adapted to function as a damper for controlling the draft in said chamber.

4. A heating appliance comprising in combination an open-front radiant heater consisting of an outer housing having an opening in its front, a perforated cover on its top, and an outwardly projecting portion above said front opening perforated on its under side to permit the circulation of air through it and out said cover, a burner supported in said housing back of said front opening, an inverted substantially L-shaped heat-reflecting back wall mounted in the rear of said burner, a plurality of radiants mounted over said burner with their upper ends engaged in an orifice in said back wall and in such a way that only the products of combustion passing through said radiants are permitted to pass through said orifice, an enclosed circulator chamber forming casing mounted adjacent the rear of said back wall and in spaced relation with said outer housing, an inlet connection connecting said casing to the orifice in said back wall, a flue connection extended from said casing through said housing, a plurality of open ended circulating conduits extended vertically through said circulator chamber, and a baffle wall structure in said casing arranged to provide a circuitous path for the products of combustion through the circulator chamber.

5. A heating appliance comprising in combination an open-front radiant heater consisting of an outer housing having an opening in its front, a perforated cover on its top, and an outwardly projecting portion above said front opening perforated on its under side to permit the circulation of air through it and out said cover, a burner supported in said housing back of said front opening, an inverted substantially L-shaped heat-reflecting back wall mounted in the rear of said burner, a plurality of radiants mounted over said burner with their upper ends engaged in an orifice in said back wall and in such a way that only the products of combustion passing through said radiants are permitted to pass through said orifice, an enclosed circulator chamber forming casing mounted back of

said back wall; an inlet connection connecting said casing to the orifice in said back wall, a flue connection extended from said casing through said housing, a plurality of open ended circulat-
5 ing conduits extended vertically through said casing, a baffle wall structure in said casing ar-

ranged to provide a circuitous path for the products of combustion through said circulator chamber, and a bottom wall for said housing having openings in it registering with the ends of said circulating conduits.
